UNITED STATES PATENT OFFICE.

GUSTAVE A. URBACH, OF PITTSBURGH, PENNSYLVANIA.

SPRAYING MACHINE.

Application filed November 2, 1921. Serial No. 512,186.

My invention relates to spraying machines and particularly to atomizing devices for applying paint.

One object of my invention is to provide a spraying machine that shall have a relatively light-weight removable handle member.

Another object of my invention is to provide a spraying machine that shall be constructed as a unit to be received by the handle member.

Another object of my invention is to provide a spray-head for a machine, of the above-indicated character, that shall be removable as a unit and that may be disposed in any desirable relation with respect to the machine.

Another object of my invention is to provide a spray-head that may be adapted for projecting any desired shape of spray.

Another object of my invention is to provide a simple method of controlling the spraying machine.

A further object of my invention is to provide a spraying machine, of the above-indicated character, that shall be simple and inexpensive to construct, easily adjusted and effective in its operation.

In practicing my invention, I provide a relatively light, two-part hollow shell having a barrel portion and a stock or handle grip portion. A unitary device comprising a paint valve, an air valve, a spray-head and a trigger are partially enclosed in the shell and constitute therewith a complete spraying machine.

Fig. 1 of the accompanying drawings is a side elevational view of a spraying machine embodying my invention;

Fig. 2 is a side view, partially in section and partially in elevation, of the spraying machine shown in Fig. 1;

Fig. 3 is a view of the end of the machine taken along the line III—III of Fig. 2;

Fig. 4 is a front view of one form of spray-head;

Fig. 5 is a front view of another form of spray-head;

Fig. 6 is a rear view of the spray-head shown in Fig. 5;

Fig. 7 is a detail view of the paint-conducting portion of the spray-head shown in Figs. 5 and 6; Fig. 8 is a longitudinal section of the spray head and paint valve; and Figs. 9 and 10 are side and end elevational views of the paint valve actuating the lever.

A spraying machine 1, embodying my invention, comprises, in general, a two-part shell 2, a spray-head 3 and a unitary valve mechanism 4.

The two-part shell 2 has a barrel portion 5 and a handle grip portion 6, which is so shaped as to be convenient for holding and which shall be constructed of a relatively light-weight material to decrease the total weight of the device and thereby render it more suitable for operation. The shell member 2 may be die-cast, if preferred, and is well balanced to facilitate holding.

The valve mechanism 4, to which the spray-head 3 may be readily connected by a sleeve connector 7, comprising an air valve 8, a paint valve 9 and an actuating device 10 for the reciprocation of members 11 and 12 thereof, respectively. The actuating device 10 comprises a trigger 13 that is pivotally mounted on a screw 14, which also assists in holding the two parts of the shell 2 together. A lever arm 15 is also pivotally mounted on a screw 16 and the lever arm 15 and the trigger 13 are connected together by a pin 17 in trigger 13 passing through a slotted opening 17^a of lever 15 to render the latter movable about its pivot 16 when the trigger is actuated.

The air valve 8 comprises a cylinder 18 having a partition intermediate the ends thereof. An inlet pipe 19 and an outlet pipe 20 are respectively connected to the cylinder 18 as shown. The member 11 of the valve 8 is adapted to be engaged by the trigger 13 and it, in turn, actuates a valve stem 21 which is normally biased by a spring 22 to the closed position. With this arrangement, the air valve 8 is opened only when the trigger is depressed.

A hose connection 23 is secured to the end of the pipe 19 by a sleeve connector 24.

A cylinder 25 is provided with a cylindrical member 26 extending radially therethrough which has a tube 27 communicating at one side thereof and a tube 28 at the other side thereof. The cylinder 25 is closed at both ends and is provided with axial openings for the tubes 27 and 28. A second opening 29 is in the head end 30 of the cylinder 25 and it communicates with the outlet pipe 20 from the air valve 8.

The reciprocating member 12 constitutes the valve stem of the paint valve 9 and has a spring seat 31 which has a groove therein that is engaged by a screw 31^a to retain it in

position in the shells 2. A spring 32 surrounds the member 12 and acts against a washer 33 that is pinned to the member 12. The member 12 is normally actuated by the 5 spring 32 to its closed position. The outer end of the member 12 is screw-threaded to receive two knurled-head nuts 34 and 35 for adjusting the movement of the member 12 and for precluding its movement when de- 10 sired.

The cylinder 26 has a screw plug 36 in its upper end and a hose connection 37 at its lower end. The hose connection is provided with a sleeve coupling 37^a to permit 15 its easy disconnection. The plug 36 is provided to facilitate cleaning the paint valve 9. The cylinder 27 has an oil port 38 for purposes of applying lubricants.

The cylinder 25 has a groove 39 at one 20 end for positioning the same in the shell 2 and with screw threads 40 at the other end to receive the sleeve connector 7 for securing the spray-head 3 thereto.

The shells 2 have seats 50, 51 and 52 25 therein to receive the air valve 8, the spring seat 31, and the lower end of the intake pipe 19, respectively. It will be noted that the valve 8 extends entirely through the shells 2 and is provided with screw plugs 30 41 and 42 at the ends thereof to facilitate assembly and cleaning.

Since the paint connection is adjacent the spray-head, it will be seen that the paint 35 passage is substantially a minimum length and that it is so accessible as to be readily cleanable.

The trigger 13, when depressed, causes the lever arm 15 to move in the same direction with a slight lag in its operation. This 40 permits a blast of air to be forced through the spray-head before the paint valve is opened. It will be understood that, by the simple operating mechanism, this slight lag is obtained and no complicated linkage 45 mechanism is necessary.

The spray-head 3, which is adapted to fit flush with the outer end 30 of the cylinder 25, comprises a conical-shaped hollow member having an opening 43 at its outer end. 50 The opening 43 may be of any desired shape, such as oblong, as shown in Fig. 5, or annular, as shown in Fig. 4, according to the shape of the spray desired. The head 3 has an internal shoulder 44 therein, against 55 which a removable member 45 normally rests. The member 45 comprises a tubular member, the inner end of which is for disposition adjacent and in axial alignment with the tube 28 and the outer end 46 of 60 which is so disposed in the opening 43 as to provide a concentric opening therearound whereby the air from the opening 29 may be discharged around the paint opening 46 and thereby, by creating a suction, cause 65 the paint to be discharged. Fins 48 sur-

round the member 45 and have tight frictional engagement with the inner surface of the spray-head.

Since the spray-head is placed in operative position by merely placing it in any desired angular position adjacent the outer end of the cylinder 25 and adjusting the sleeve connector 7, it is possible to easily assemble a spray-head having other than circular orifices. 75

A plurality of screws 47 are provided for holding the shells together.

The nuts 34 and 35, when moved to the extreme outer end of their travel, preclude the opening of the paint valve when the trigger is depressed, as the forked end of the lever does not engage the nuts and, consequently, the spring 32 maintains the valve stem 12 in its closed position. Under this condition, when the trigger is depressed a 85 blast of air only is delivered.

The main features of my invention are its lightness, simplicity of the operating mechanism and its unitary parts which render it 90 very simple to assemble. By reason of the fact that the member 45 frictionally is held in place in the spray-head, it is essentially a unitary device and may be connected to the spraying machine by a simple sleeve coupling or connector 7. 95

My invention is not limited to any particular form of spray-head, as my new combination permits any desired form being used. I further do not limit my invention to the structural features shown, as many 100 changes may be made therein without departing from the spirit and scope of the same, as set forth in the appended claims.

I claim as my invention:

1. A paint valve for a spraying device comprising a cylindrical member, a pipe connection at one end, a closure screw at the other end and a valve stem passing laterally through one side of the cylindrical member and seated in an opening in the other side thereof. 105

2. A valve device for a spraying machine comprising a cylindrical member having alined relatively small openings in both ends, a second cylindrical member disposed transversely through the other cylindrical member, a closure for one end of the second cylindrical member, and a hose connection on the other end thereof, a valve stem disposed longitudinally in the first cylindrical member through one opening therein and seated in one side of the second cylindrical member, the other opening in the first cylindrical member being the valve outlet. 115

3. A valve device for a spraying machine comprising a cylindrical member having alined relatively small openings in both ends, a second cylindrical member disposed transversely through the other cylindrical member, a closure for one end of the second cy- 120

125

130

- lindrical member, and a hose connection on the other end thereof, a valve stem disposed longitudinally in the first cylindrical member through one opening therein and seated in one side of the second cylindrical member, the other opening in the first cylindrical member being the valve outlet, and means for securing a spray-head adjacent the last opening.
- 10 4. A spraying machine comprising a cylindrical member having a substantially plane end with an axial opening and a non-centrally disposed opening therein, a conical member having a central portion for registering with the axial opening, a concentric opening disposed entirely around the central portion in communication with the non-centrally disposed opening, and a union for connecting the conical member to the cylindrical member without relative rotation thereof.
- 15 5. A spraying machine comprising a cylindrical member having a substantially plane outer end with a plurality of openings therein, a conical member having a central portion extending through an opening in the
- outer end thereof, and means for securing the conical member to the plane outer end of the cylindrical member.
6. A spraying machine comprising a cylindrical member having a substantially plane outer end with a plurality of openings therein, a conical member having a central portion extending through an opening in the outer end thereof, and a union for securing the conical member to the outer end of the cylindrical member. 30
7. A spraying machine comprising a cylindrical member having a substantially plane outer end with a plurality of openings therein, a conical member having a central portion extending through an opening in the outer end thereof, and a union for securing the conical member in any desired relation to the outer end of the cylindrical member. 35
- 40
- 45
- In testimony whereof, I have hereunto subscribed my name this 17th day of Oct., 1921.

GUSTAVE A. URBACH.
